UNITED STATES PATENT OFFICE

158,640

CLOTHESLINE REEL

Arthur B. Bok, Fort Wayne, Ind.

Application January 26, 1949, Serial No. 517

Term of patent 7 years

(Cl. D49—1)

To all whom it may concern:

Be it known that I, Arthur B. Bok, a citizen of the United States and resident of Fort Wayne, in the county of Allen and State of Indiana, have invented a new, original, and ornamental Design for a Clothesline Reel, of which the following is a specification, reference being had to the accompanying drawing, forming a part thereof.

In the drawings, Fig. 1 is a perspective view of a clothesline reel embodying my new design, and Fig. 2 is a top view thereof.

I claim:

The ornamental design for a clothesline reel, substantially as shown.

ARTHUR B. BOK.
